Primary Examiner—Ian Simmons*Assistant Examiner*—Dana Sipos(74) *Attorney, Agent, or Firm*—Buchanan Ingersoll & Rooney PC**CLAIM**

The ornamental design for a packaging, as shown and described.

DESCRIPTION

FIG. 1 is a top, front perspective view of a packaging showing my new design.

FIG. 2 is a front elevational view thereof.

FIG. 3 is a right side elevational view thereof.

FIG. 4 is a left side elevational view thereof.

FIG. 5 is a rear elevational view thereof.

FIG. 6 is a bottom plan view thereof.

FIG. 7 is a top plan view thereof.

FIG. 8, is a top, front perspective view of the packaging of FIG. 1 with the cap removed.

FIG. 9 is a front elevational view thereof.

FIG. 10 is a right side elevational view thereof.

FIG. 11 is a left side elevational view thereof.

FIG. 12 is a rear elevational view thereof.

FIG. 13 is a bottom plan view thereof; and,

FIG. 14 is a top plan view thereof.
